UNITED STATES PATENT OFFICE.

HENRY ARMBRUSTER, OF WOODBURN, INDIANA.

POST PULLER.

Application filed January 11, 1924. Serial No. 685,598.

To all whom it may concern:

Be it known that HENRY ARMBRUSTER, a citizen of the United States, residing at Woodburn, in the county of Allen and State 5 of Indiana, has invented certain new and useful Improvements in Post Pullers, of which the following is a specification.

This invention relates to new and useful improvements in post pullers, and has for 10 its principal object to provide a simple device which may be readily set up in an operative position for the purpose of removing or extracting decayed posts or stumps from the ground.

15 Another important object of the invention is to provide a post puller of the above mentioned character, which is of such a construction as to prevent the accidental displacement of the post engaging means from 20 its operative position around the post while the latter is being raised.

25 A further object of the invention is to provide a post puller of the above mentioned character which when placed in an operative position with respect to the post to be raised will permit the post engaging means to firmly grip the post in such a manner as to prevent the possibility of any lateral strain on the post, thus preventing 30 the post from breaking off at a point adjacent the ground.

35 Another important object of the invention is to provide a post puller of the above mentioned character, which is especially adapted for use in raising telegraph poles, trees, or the like, in a quick and efficient manner.

40 A further object of the invention is to provide a post puller of the above mentioned character, which is simple in construction, strong and durable, inexpensive, and further well adapted for the purposes for which it is designated.

45 Other objects and advantages of this invention will become apparent during the course of the following description.

In the drawing forming a part of this specification and in which like numerals designate like parts throughout the same,—

50 Figure 1 is a side elevation of my device

showing the same in connection with a pole.

Figure 2 is a front elevation thereof.

Figure 3 is a detail view of the post engaging means, and

Figure 4 is a detail view of the detach- 55 able unit adapted to be associated with the endless chain, and the post engaging means.

In the drawing wherein for the purpose of illustration is shown the preferred embodiment of my invention, the numeral 1 60 designates generally the support forming my invention and comprises the vertical standards 2 and 3, respectively. Each standard tapers smaller towards its upper end and adapted to be supported on the 65 upper end of each standard by suitable fastening means such as is shown at 4 in the drawing, is the bracket or casting 5. Each bracket is preferably supported on the front face of each standard, as is clearly illustrated in Fig. 2 of the drawing, and the bracket, furthermore, is provided with an opening 6 adjacent the upper end thereof and a similar opening 7 adjacent the lower end thereof, the purpose of which will hereinafter be more fully described. A similar bracket 8 is mounted on the lower front face of each standard and is also provided with an opening 9, as is clearly illustrated 70 in the drawing, preferably Fig. 1. 75

80 A suitable brace 10 is adapted to extend through the openings 9 in the bracket 8 supported on the lower end of each standard for holding the same in proper spaced relation, and this brace or shaft 10 is so mounted in the opening 9 of each bracket as to be rotatably supported therein. Keyed to the shaft 10 intermediate its ends is the 85 sprocket wheel 11.

Extending through the registering open- 90 ings 6 provided in the upper portion of each bracket 5 is the shaft 12. One of the ends of this shaft extends for a substantial distance beyond the side of the standard 3, as clearly illustrated in Fig. 2 95 of the drawing, and mounted thereon is the gear wheel 13. Any suitable means may be associated therewith for securing the gear wheel in a locked position on the shaft so as to rotate therewith. A similar shaft 14 100

is adapted to extend through the lower openings 7 of each bracket 5, and keyed on the shaft 14 beyond the side of the standard 3 is the pinion 15. This pinion is so arranged on the shaft as to mesh with the gear wheel 13, whereby the latter may be driven thereby. A suitable handle or the like such as illustrated at 16 in the drawing is mounted on the free end of the shaft 14 adjacent the pinion 15 for actuating the same. A sprocket wheel 17 similar to the sprocket wheel 11 is keyed on the shaft 12 and is arranged in vertical alignment with the sprocket wheel 11 and adapted to extend around these aligning sprocket wheels is an endless sprocket chain designated by the numeral 18.

This sprocket wheel may be of any suitable construction as is well known in the art. Formed on certain of the links of the sprocket chain 18 are the hooks 19. Certain of the links have these hooks 19 extending laterally from the sides thereof, as is clearly illustrated in Fig. 2 of the drawing, and the purpose of this arrangement will be hereinafter more fully described. These hooks are so arranged as to have the free ends thereof extending upwardly and as many of these links having the hooks formed thereon may be provided as is necessary, and I do not wish to limit myself to the particular number or arrangement of the links and hooks associated therewith.

Also forming a part of the present invention is the post engaging means, which in the present instance is in the formation of a flexible chain and is further illustrated at 20 in the drawing. One end of the chain is provided with a hook 21 for the well known purposes, and when the chain is wrapped around the post to be raised in the manner as will be presently described, the hook 21 will engage one of the links of the chain and hold the same in position around the post, while the opposite end of the chain is adapted to be placed on the hooks 22 which are provided on the lower portion of the unit 23, the upper portion of which is provided with the downwardly turned hooks 24. The downwardly turned hooks 24 are adapted to engage a pair of the upwardly extending hooks 19 carried by certain of the links of the sprocket chain 18.

In operation, the device is so arranged or set up as to have the sprocket chain 18 extending substantially parallel and adjacent the post A, which is to be raised and the chain 20 is then placed around the upper portion of the post or at any desired point thereon, and after the chain has been wrapped around sufficiently to insure against the accidental displacement from the post, the unit 23 is then brought into engagement with the post engaging chain by having the hooks 22 receiving the free end of the chain

20, and the hooks 24 formed on the upper end of the unit are then brought into engagement with the nearest pair of upwardly extending hooks 19 provided on the sprocket chain 18. The operator then actuates the handle 16 so as to cause the pinion 15 to operate the gear wheel 13, whereby a rotary movement is imparted to the shaft 12 and the sprocket wheel 17 keyed thereon, thus raising the endless chain 18 and consequently resulting in the raising or lifting of the post from the ground.

If desired, a suitable pawl and ratchet means may be associated with the driving shaft 14 for holding the same in a predetermined position so as to prevent the accidental return of the sprocket chain 18, and thereby enable the post to be supported in a raised position, so that the same may be easily and quickly removed and transported.

It will thus be seen from the foregoing description that a simple and efficient device has been provided which will enable stumps and posts of various kinds to be easily removed from the ground, the device being so arranged and operated in such a manner as to prevent the possibility of any lateral strain on the post while the same is being raised which would ordinarily result in the breaking off of the post adjacent the ground.

From the foregoing description of the construction of my improved apparatus, it will be seen that I have provided a simple, inexpensive and efficient means for carrying out the objects of the invention, and while I have particularly described the elements best adapted to perform the functions set forth, it is obvious that various changes in form, proportion, and in the minor details of construction may be resorted to, without departing from the spirit or sacrificing any of the principles of the invention.

Having thus described my invention what I claim as new and desire to secure by Letters Patent is:—

1. In a device of the class described comprising a vertical standard, fastening means thereon, comprising brackets, spaced shafts mounted in said brackets and carrying sprocket wheels, an endless chain mounted on said sprocket wheels, means for actuating the same, a flexible member adapted to encircle a post, hooks formed on certain of the links of said endless chain, and a detachable unit having hooks formed on the lower end thereof for engagement with said flexible member, and hooks being provided on the upper end of said unit for engagement with said hooks on said endless chain, substantially as described.

2. A post puller of the class described comprising vertical supports tapered to

wards their upper ends, fastening means comprising an upper bracket, openings in the upper and lower ends thereof, shafts extending through said openings, meshing gear wheels on said shafts, an endless chain mounted on said upper shaft, means for actuating the same comprising a handle on the shaft mounted in the lower opening of the bracket, a flexible chain adapted to encircle a post, upstanding hooks formed on

certain of the links of said endless chain, a detachable unit having hooks formed on the lower end thereof for engagement with the flexible post encircling chain, and hooks formed on the upper portion of said unit for engagement with said upstanding hooks, substantially as described.

20 In testimony whereof I affix my signature.

HENRY ARMBRUSTER.
